POCKET HYGROMETER

Hiram Marcus Dean, Berkeley, Calif.

Application June 8, 1953, Serial No. 360,261

2 Claims. (Cl. 73—337)

My present invention relates to a convenient pocket device and more particularly to a new and novel pocket hygrometer by which atmospheric conditions may be determined.

The object of my invention is to provide a novel hygrometer that can be conveniently carried in the pocket and exposed to the atmosphere to determine ambient weather conditions.

Another object of my invention is to provide an improved hygrometer having means by which the sensitive hygrometer element may be protected against body heat or the like when not in actual use.

Other objects and advantages of my invention will be in part evident to those skilled in the art and in part pointed out hereinafter in connection with the accompanying drawing wherein there is shown by way of illustration and not of limitation a preferred embodiment thereof.

In the drawing:

Figure 1 is a vertical view of my improved device, partly in section and revealing details of construction,

Figure 2 is a horizontal sectional view taken along line II—II of Figure 1,

Figure 3 is a similar sectional view taken along line III—III of Figure 1,

Figure 4 is a view similar to Figure 3 showing the parts in different relative positions.

Figure 5 is a horizontal sectional view taken along line V—V of Figure 1, and

Figure 6 illustrates a variation of the invention as distinguished from the showing in Figure 2.

A feature of my present invention resides in its simplicity of construction. To this end, as will be described, I employ a simple twisted cat gut element of such construction that it requires no tensioning means, but rather extends normally upward from a fixed support and freely through a guide at its other end. Another feature resides in the provision of a novel enclosure for the sensitive cat gut which will protect the operating element from body heat or other abnormal conditions when not in use.

For a more detailed description of the invention reference is now made to Figure 1 of the drawings, wherein I have shown a pencil unit 10 having lead 11, at one end and to the other end of which there is applied a hygrometer device, designated generally by the numeral 12. As here shown the hygrometer device 12 is attached as a whole to the pencil 10 by a surrounding sleeve 13, into which the upper end of the pencil 10 is secured. Extending downwardly into the sleeve 13 there is a tubular member 14 having a plurality of circumferentially spaced elongated slots 15. At its upper end the tubular member 14 is closed by a convexed lens forming member 16, which may be of an optical glass or a plastic such as "Lucite." At the lower end of the tubular member 14 there is a relatively fixed plug like member 17. Secured to this plug like member 17 and extending upwardly into the tubular member 14 there is a moisture responsive length of stiff, twisted cat gut 18. At its upper end the cat gut element

2

18 extends through a second adjustable plug 19 that has a suitable bearing opening 20 in which the cat gut freely turns. At its outer end the cat gut element 18 carries a pointer 21 that is associated with an indicating chart or scale upon the outer face of the plug 19. As here shown the plug 19 also carries a stop 22 to limit the turning movement of the pointer 21 within the limits of the scale or chart when the device is in operation.

In order to protect the cat gut element from extreme conditions and/or when not in use and to further facilitate the use of my improved unit with a pencil or pen I provide an outer sleeve or tubular member 23, which carries a pocket clip 25 such as is commonly provided with pocket pencils as a means for securing the pencil against loss. This outer sleeve 23 completely surrounds the tubular member 14 and is free to turn with respect thereto. The outer sleeve or tubular member 23 is also provided with circumferentially spaced elongated slots 24 that are adapted when in one position to register with the elongated slots 15 of the tubular member 14 and when in another position to form a complete enclosure for the cat gut element 18.

As shown in Figure 2, of the drawing the plug member 19 may be provided with a chart, here shown as divided into quarters, with weather indicating indicia applied to each of these quarters. In this particular showing the stop 22 with which the indicating pointer 21 cooperates is positioned between the two quarters designated respectively to indicate a period of dry weather or a period of rain. The other two quarters of the chart are here marked to designate respectively a condition of clear or variable weather. With this arrangement it will be seen that in moving from an indication of dry atmospheric conditions to an indication of rain, the pointer 21 will travel through the four weather indicating zones in the order of dry, clear, variable, and finally rain where the pointer 21 will come to rest at the other side of the stop 22.

In Figure 3 of the drawing the outer sleeve 23 with its clip 25 is shown as in a position with the elongated slots 24 thereof in register with the slots 15 of the inner sleeve 14. When the slots 15 and 24 are in register in this manner the cat gut element 18 will be exposed to the ambient weather conditions and as the pointer 21 comes to rest the particular weather condition prevailing will be indicated upon the chart carried by the plug 19.

As shown in Figure 4 of the drawing when the hygrometer is not in use, as when the pencil is returned to the pocket or laid away, the outer sleeve 23 may be rotated by turning the clip 25 with respect to the pencil. In this way the elongated slots 24 of the outer tubular sleeve 23 and at elongated slots 15 of the inner sleeve 14 can be positioned out of register and thus completely enclose the sensitive cat gut element 18.

As shown in Figures 1 and 5, the plug member 17, to which the cat gut element 18 is permanently affixed, has a central opening into which the lower end of the cat gut 18 is extended and as a means for securing the cat gut 18 rigidly within this member, I employ a wedge 26 that is driven into the central opening of the plug 17 when the end of the cat gut 18 has been positioned therein. After assembly in this manner it is contemplated that the pointer 21 at the upper end of the cat gut 18 will be adjusted with respect to the chart carried by the plug member 19 by turning the plug 17 within the sleeve 14. To this end the under side of the plug 17 is shown as having spanner wrench recesses 27 by which it may be turned relative to the tubular member 14. At this point it will be noted that the plug 17 is shown as held into the tubular member 14 by a tight drive fit. This provides for an independent axial or rotary adjustment of the plug 17 without disturbing its adjustment in the other respect.

In Figure 6, of the drawing there is shown a variation

of the invention in which the printed word designations are omitted and a color arrangement is substituted therefor. In this embodiment the "dry" quadrant is indicated as yellow in color, the "clear" quadrant is blue in color, the "variable" quadrant is red in color, and the "rain" quadrant is black in color. This latter arrangement is suggested for the reason that due to the size of the end of the pencil it may be difficult to apply and/or read printed designations such as are described in connection with Figure 2 of the drawing.

While I have, for the sake of clearness and in order to disclose the invention so that the same can be readily understood, described and illustrated specific devices and arrangements, I desire to have it understood that this invention is not limited to the specific means disclosed, but may be embodied in other ways that will suggest themselves to persons skilled in the art. It is believed that this invention is new and all such changes as come within the scope of the appended claims are to be considered as part of this invention.

Having thus described my invention, what I claim and desire to secure by Letters Patent is:

1. In a pocket hygrometer, the combination of an open ended cylindrical member having circumferentially spaced longitudinally extending slots formed therein, a dial carrying plug mounted within one end of said cylindrical member having a central opening and weather indicating indicia upon its exposed end, a rotatably and axially adjustable plug-like support frictionally held in the other end of said cylindrical member, a length of stiff, twisted moisture sensitive material secured at one end upon said plug-like support and extending centrally into said cylindrical member with its free end projecting through the central opening of said dial carrying plug, a pointer secured upon the free end of said moisture sensitive material for co-operation with the weather indicating indicia upon said dial carrying plug, said pointer being properly related to the weather indicating indicia upon said dial carrying plug by rotary and axial adjustments of said plug-like support, and a cylindrical protective sleeve mounted externally upon said cylindrical member having spaced longitudinally extending slots adapted and arranged upon a rota-

tion of said sleeve to respectively expose and conceal said moisture sensitive material when its slots are moved into and out of register with the slots of said cylindrical member.

- 5 2. In a pocket hygrometer, the combination of an open ended cylindrical member having circumferentially spaced longitudinally extending slots formed therein, a dial carrying plug mounted within one end of said cylindrical member having a central opening and weather indicating indicia upon its exposed end, a plug-like support extending with a tight fit into the other end of said cylindrical member, a length of stiff, twisted moisture sensitive material secured at one end upon said plug-like support and extending centrally into said cylindrical member 10 with its free end projecting through the central opening of said dial carrying plug, a pointer secured upon the free end of said moisture sensitive material for co-operation with the weather indicating indicia upon said dial carrying plug, a cylindrical protective sleeve rotatably mounted 15 upon said cylindrical member having a pocket engaging clip and spaced longitudinally extending slots adapted and arranged upon rotation of said sleeve to be brought into and out of register with the circumferentially spaced longitudinally extending slots of said cylindrical member 20 to respectively expose and conceal said moisture sensitive material when said protective sleeve is rotated about said cylindrical member.
